GAGE-GLASS.

1,136,468.

Specification of Letters Patent.

Patented Apr. 20, 1915.

Application filed April 25, 1913. Serial No. 763,541.

To all whom it may concern:

Be it known that we, WILLIAM J. HANLON and JOHN H. HANLON, citizens of the United States, residing, respectively, at Fitchburg, county of Worcester, Massachusetts, and Somerville, county of Middlesex, State of Massachusetts, have invented a certain new and useful Improvement in Gage-Glasses, of which the following is a specification, reference being had therein to the accompanying drawings.

Our invention relates to water gages of the class employed on steam boilers to indicate the height of the water in the boiler and relates particularly to water gages of the so-called bull's-eye type. Heretofore, so far as we have known, the blowing off of these gages essential to rid them of the usual sediment and deposit collected therein has resulted in doing material injury to the bull's-eyes used in the construction of the gage, so that they soon become clouded and weakened thereby necessitating the frequent renewal of the same.

25 The object of our invention, therefore, is to produce a gage glass, which may be blown off and thoroughly cleaned inside without the slightest injury to the glass and furthermore, which is so constructed that dirt, 30 and the like may be readily removed from the outer glass surfaces.

Our invention consists in certain novel features of construction and arrangement, all as hereinafter more fully set forth in the 35 following description of a device embodying our invention and illustrated in the accompanying drawings forming a part hereof.

The novel features of our invention are clearly defined and pointed out in the claims 40 at the close of the specification.

In the drawings, Figure 1 is a side elevation of a water gage embodying our invention. Fig. 2 is a section on line 2—2 of Fig. 1. Fig. 3 is a section on line 3—3 of Fig. 1.

45 Having reference to the drawings, and particularly to Fig. 1, there is shown at A the metallic frame or body of our improved gage glass. This is preferably made of bronze and is capable of withstanding the 50 pressure to which it is subjected.

At B is a lateral extension or lug designed to be used in combination with a bracket C, to which it is secured by a bolt 12, the gage glass thereby being held in the proper position upon the boiler.

On each face of the water gage, there are glass bull's-eyes arranged in two vertical rows, as shown in Fig. 1, those in one row being indicated by the numerals 13 and those in the other row by the numerals 14. 60 The bull's-eyes are so arranged that the upper portion of one overlaps the lower portion of another, as is clearly shown in Fig. 1. We have placed the bull's-eyes in this staggered relation in order that the level of 65 the water or other liquid in the gage may be clearly visible through some one of the bull's-eyes. While we prefer to adopt the arrangement shown it will be clear that the number of bull's-eyes may be increased or decreased. 70

The opposite face from that shown in Fig. 1 is provided with a like number of bull's-eyes, there being one bull's-eye directly in line with each of the bull's-eyes shown, as 75 will be clear from Fig. 2.

Each of the bull's-eye holes, as is shown at 16 in Fig. 2, is provided with a flange 17. Each glass bull's-eye has a rib 18 for the purpose hereinafter set forth. A gasket 19 80 is located between each rib 18 and the flange 17 at each bull's-eye hole in the frame. A second gasket 20 is placed outside of each rib 18 and is abutted by a collar 21 threaded into each bull's-eye hole. The screwing in 85 of the collars 21, by means of notches 221, brings pressure against the gaskets 19 and 20 which fit tightly into the bull's-eye holes and operates to secure the glass bull's-eyes firmly in place and prevent any leakage. 90

The collars 21 fit snugly around the bull's-eyes and their outer portions are outwardly flared interiorly, and the outer faces or parts of the bull's-eyes extend out into the larger openings so formed, thus providing 95 annular spaces 22 around the outer faces or parts of the bull's-eyes. This is a desirable feature of our gage-glass, as it has been found in the past that the outer faces of the bull's-eyes become covered with dirt, grease 100 and the like, and heretofore these faces could not be kept clean without an amount of trouble which engineers will not take, in ordinary practice. The annular spaces 22, however, render all of the outer glass surfaces accessible to be readily cleaned by wiping, since there is nothing at the peripheral edges of the bull's-eyes to interfere. 105

The inner surfaces of the bull's-eyes and 110

portions of the frame or body A, including the flanges 17, form a central vertical chamber 23 extending between the vertical rows or tiers of bull's-eyes, and which chamber, in horizontal section, is thin or narrow in one direction and thick or wide in another direction. At the upper end of this chamber is a top or inlet mounting 24 which is threaded into the boss 25 at the top of the frame A, and at the lower end of the chamber is a bottom mounting 26 threaded into the boss 27. To the top mounting 24 is secured a tube 28 which extends downwardly centrally through the chamber 23 to a point a short distance above the opening in the bottom mounting 26, said opening providing an outlet from the chamber 23, and which outlet is inwardly or upwardly flaring, at 261.

20 The tube 28 extends to a point near the bottom of the chamber 23. This tube 28 serves to keep the hot steam away from the inner faces of the bull's-eyes and also from the frame or body A, so far as is possible, and owing to the fact that the said tube extends to a point near the bottom of the chamber 23 the column of down-rushing steam expands in said chamber after leaving the mouth or outlet end of the tube, and in so doing agitates the water and causes it to circulate in said chamber and thus disturb any scale or mud which may accumulate in the lower part of the gage-glass, thereby thoroughly cleansing the inner faces of the bull's-eyes.

25 We provide the upper end of the tube 28 with two ports 29, leading into the chamber 23. In blowing off the gage, to remove the sediment, the steam will mainly pass downwardly from the inlet mounting 24, through the tube 28 and thence out through the passage in the bottom mounting 26. It will thus be seen that there is therefore no rush of highly heated steam across the inner faces of the upper bull's-eyes, which we believe has been the cause of the rapid deterioration and clouding of the bull's-eyes in the past. The passage of the steam from the tube 28 into the orifice of the exhaust connection causes a suction and tends to lower the pressure in the chamber outside of the tube. The two ports 29 in the upper end of the tube permit the passage of steam into the upper end of the chamber 23, and therefore when the blowing off is completed the pressure throughout the chamber is equalized and the water will assume the level of the water in the boiler.

30 By carrying the steam through the body of the gage to the bottom thereof the body of the gage and the bull's-eyes are not suddenly heated by the inrush of steam at much higher temperature, and therefore the metal body is not suddenly expanded and contracted and consequently the bull's-eyes are

not loosened in the body nor broken, nor are the gaskets attacked by the highly heated steam, the inner gaskets being protected by the flanges 17, as will be readily understood.

35 In blowing out the gage, for the purpose of cleansing the same, the lower valve shown in Fig. 1 in the water pipe leading from the boiler is not closed, and when the gage discharge cock is opened, and the pressure in the chamber of the gage is consequently lowered, high pressure steam is discharged from the tube 28 into the lower part of the chamber 23 where it expands and causes such an agitation or whirling about of the 40 water and steam in said chamber as will effectively remove sediment and scale from the inner faces of the bull's-eye glasses. Owing to the lowered pressure in the chamber 23 the water from the pipe leading to 45 the boiler, or the lower boiler mounting, flows upward as well as downward, thereby retarding the discharge of water from the chamber of the gage glass in such a manner that the glass will be thoroughly 50 cleansed internally before said chamber is emptied of water.

55 What we claim is:—

1. An improved water gage consisting of a metallic frame or body, vertical rows or 60 tiers of bull's-eye glasses fitted therein and separated from each other forming a central water chamber between the inner faces of the bull's-eyes, and a steam tube extending from the top of said chamber to near the 65 bottom thereof so that the lower end of said tube opens into said chamber in such a manner that when steam is admitted to said tube the water in said chamber will be agitated to cleanse the inner faces of the 70 bull's-eyes. 100

2. An improved water gage consisting of a metallic frame or body, vertical rows or tiers of bull's-eye glasses fitted therein and separated from each other forming a central water chamber between the inner faces of the bull's-eyes, a top or inlet tubular mounting attached to said frame or body, and a steam tube attached to said top mounting and extending from the top of said chamber to near the bottom thereof so that the lower 115 end of said tube opens into said chamber in such a manner that when steam is admitted to said tube the water in said chamber will be agitated to cleanse the inner faces of the 120 bull's-eyes. 110

3. An improved water gage consisting of a metallic frame or body, vertical rows or tiers of bull's-eye glasses fitted therein and separated from each other forming a central water chamber between the inner faces of the bull's-eyes, a top or inlet tubular mounting attached to said frame or body, and a steam tube attached to said top mounting and extending from the top of said chamber to near the bottom thereof so that the lower 125 130

end of said tube opens into said chamber in such a manner that when steam is admitted to said tube the water in said chamber will be agitated to cleanse the inner 5 faces of the bull's-eyes, and a lower or outlet tubular mounting at the bottom of said chamber providing an inwardly flaring outlet from said chamber.

4. An improved water gage comprising a 10 metallic frame or body, vertical rows or tiers of bull's-eye glasses, a central water chamber, and a steam tube extending from the top of said chamber to a point near the bottom thereof, so that said tube may discharge 15 steam into the water at a little distance above the bottom of said chamber, thereby causing the water to be agitated or whirled about in said chamber so as to cleanse the inner faces of the bull's-eyes before it is 20 discharged from the gage.

5. An improved water gage comprising a

metallic frame or body, vertical rows or tiers, of bull's-eye glasses, a central water chamber, and a steam tube extending from the top of said chamber to a point near the 25 bottom thereof, so that said tube may discharge steam into the water at a little distance above the bottom of said chamber, thereby causing the water to be agitated or whirled about in said chamber so as to 30 cleanse the inner faces of the bull's-eyes before it is discharged from the gage, said tube having ports at its upper end leading into said chamber, to equalize the pressure 35 therein.

In testimony whereof we affix our signatures, in presence of two witnesses.
